[57] CLAIM

The ornamental design for a display rack, as shown and described.

DESCRIPTION

FIG. 1 is a perspective view from the left side of the display rack embodying my new design;

FIG. 2 is a right side elevational view, the left side elevational view being a mirror image thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a perspective view from the left of a second embodiment of that shown in FIG. 1;

FIG. 8 is a right side elevational view, the left side elevational view being a mirror image thereof;

FIG. 9 is front elevational view thereof;

FIG. 10 is a rear elevational view thereof;

FIG. 11 is a top plan view thereof; and,

FIG. 12 is a bottom plan view thereof.
